(57) **CLAIM**

I claim the ornamental design for a battery charger, as shown and described.

DESCRIPTION

FIG. 1 is a right perspective view of the battery charger; FIG. 2 is a left perspective view of the battery charger shown in FIG. 1;

FIG. 3 is a front view of the battery charger shown in FIG. 1;

FIG. 4 is a rear view of the battery charger shown in FIG. 1;

FIG. 5 is a right side view of the battery charger shown in FIG. 1;

FIG. 6 is a left side view of the battery charger shown in FIG. 1;

FIG. 7 is a top view of the battery charger shown in FIG. 1; and,

FIG. 8 is a bottom view of the battery charger shown in FIG. 1.

The subject matter shown in dashed lines form no part of the claimed invention.

(Continued)

The broken lines in the drawings are for the purpose of illustrating elements of the battery charger that form no part of the claimed design.
